GAME BOARD

Alphonso F. Stanonis, Des Plaines, Ill.

Application November 12, 1958, Serial No. 53,347

Term of patent 14 years

(Cl. D34—5)

Fig.2

I claim:

The ornamental design for a game board, substantially as shown.
